Primary Examiner — Michael A Maharajh(74) *Attorney, Agent, or Firm* — Brooks Kushman P.C.(57) **CLAIM**

The ornamental design for a massager, as shown and described.

DESCRIPTION

FIG. 1 is a perspective view of a massager showing our new design;

FIG. 2 is a right side view of the massager;

FIG. 3 is a left side view of the massager;

FIG. 4 is a front view of the massager;

FIG. 5 is a rear view of the massager;

FIG. 6 is a top view of the massager; and,

FIG. 7 is a bottom view of the massager.

The broken lines shown in the drawings are for the purpose of illustrating portions of the massager, which form no part of the claimed design.

1 Claim, 4 Drawing Sheets(56)
